UNITED STATES PATENT OFFICE.

HARRY W. HAMILTON, OF INDIANAPOLIS, INDIANA, ASSIGNOR TO THE HAM-MEIX MANUFACTURING COMPANY, OF INDIANAPOLIS, INDIANA, A CORPORATION OF INDIANA.

STARTING DEVICE FOR INTERNAL-COMBUSTION ENGINES.

1,149,132.

Specification of Letters Patent.

Patented Aug. 3, 1915.

Application filed May 27, 1912. Serial No. 699,971.

To all whom it may concern:

Be it known that I, HARRY W. HAMILTON, a citizen of the United States, residing at Indianapolis, in the county of Marion and 5 State of Indiana, have invented a new and useful Starting Device for Internal-Combustion Engines, of which the following is a specification.

It is the object of my invention to provide 10 a simple and positive starter for internal combustion engines, which shall act uniformly and without violence on the engine, requires the expenditure of a minimum amount of energy, is easily and inexpensively maintained, and is fool-proof. In 15 attaining this object, I provide a gas generator, of any suitable gas, which, preferably automatically, maintains, or rather replenishes, its pressure as gas is drawn from 20 it and is automatically protected against excessive rises in pressure from "over-generation." The gas from this generator is supplied through a control valve and a distributor to the engine cylinder or cylinders, 25 each cylinder being provided with a valve connecting it to the distributor and conveniently controlled by the same handle which operates the control valve. The distributor is arranged not only to admit fluid 30 under pressure to the engine cylinder or cylinders on their explosion strokes, but to relieve the compression within such cylinder or cylinders when on their compression strokes. In order further to guard against 35 waste and inefficiency, the gas generator is automatically cut off from the engine whenever the pressure falls below a predetermined value, thus giving the generator time to build up a pressure high enough for efficiency, in case of heavy drafts of gas therefrom; with the generator shown, the time is ordinarily but a few seconds.

The accompanying drawings illustrate my invention. In these drawings, Figure 1 is 45 a semi-diagrammatic view showing the system in its entirety and some of the parts in structural detail; and Fig. 2 is a section through the distributor on the line 2-2 of Fig. 1.

50 The generator comprises a gas generating tank 10 in which a quantity of calcium carbide 11, (if the gas used is acetylene, which has some advantages but is not essential to my invention,) or, other suitable substance,

is placed, and a liquid tank 12 for supplying 55 water or other reagent to the gas tank to react with the calcium carbide or other substance in the latter to produce acetylene or other gas. The liquid tank 12 is usually considerably smaller than the gas tank 10, 60 and the latter may be many times smaller than the tanks ordinarily used in connection with starters operating by direct fluid pressure. The two tanks are connected by a pipe 13 leading from the top of the gas 65 tank 10 and conveniently provided with a hand shut off valve 14, a pipe 15 leading from the bottom of the water tank 12, and a pressure governor for controlling the pressure above the water in the tank 12. This 70 governor comprises a diaphragm 19 clamped between two casing sections 20 and 21, a smaller diaphragm 22 clamped between the casing section 20 and a third casing section 23, a valve stem 24 which passes 75 through the diaphragm 22 and is clamped thereto by clamping nuts 25 and is provided with a head 26 which bears against that side of the diaphragm 19 which is toward the casing section 20, and an adjustable spring 80 27 which holds said head 26 against the diaphragm 19 and thus determines the pressure at which the pressure governor operates. The pipes 13 and 15 lead into the casing section 23 on the side of the diaphragm 22 85 remote from the diaphragm 19, the needle point on the valve stem 24 engaging its valve seat on the casing section 23 when the diaphragm 19 is moved against the action of the spring 27. This movement of the 90 diaphragm 19 is obtained by connecting the casing section 21 with the top of the tank 10, as by means of a pipe 28 in which may be located a hand shut off valve 29. The purpose of the diaphragm 22 is to prevent 95 the pressure in the tank 10 from acting against the side of the diaphragm 19 which is toward the casing section 20, said latter casing section being either closed or provided with vent openings 30.

100 The tank 10 is provided with a removable head 31 at one end, or at each end if desired, this head 31 being held by swinging bolts 31' to a ring 32 brazed or otherwise firmly attached to the body of the tank. The ring 105 32 and head 31 preferably fit together by interfitting ridges and grooves, as illustrated, to assist in making the joint gas-

tight, suitable gaskets being provided where necessary. By removing the head or heads 31, the tank may easily be cleaned out when desired. A removable screw plug 33 fits into a hole in the head 31, an inwardly opening check valve 34 being screwed into the inner end of this opening. By removing the plug 33, an initial charge of water or other reagent may be introduced into the tank 10 by means of a suitable syringe projected into the opening. The check valve 34 prevents the gas which is immediately generated from escaping before the plug 33 can be replaced.

As gas is drawn from the tank 10, the gas pressure above the water or other reagent in the water tank 12 forces the latter through the pipe 15, the pressure governor, and the pipe 13 into the gas tank 10. This water reacts with the calcium carbide in the latter tank, and produces more acetylene, (assuming acetylene to be the gas used,) the pressure of which forces the water still in the pipes 13 and 15 back into the tank 12, gas from the tank 10 bubbling through the water in the tank 12 to maintain, or rather replenish, the pressure above such water. When the pressure reaches a predetermined value in the tank 10, the diaphragm 19 is moved by such pressure against the spring 27 to bring the point of the valve stem 24 into engagement with its valve seat, thus shutting off the connection between the two tanks 10 and 12 and preventing the gas pressure above the water in the tank 12 from exceeding a predetermined value. As the capacity of the pipes 13 and 15 is comparatively small, the value of the pressure above the water in the tank 12 is thus maintained substantially constant, regardless of the quantity of water withdrawn, and "over-generation" due to the successive building up of the pressure above the water in the tank 12 is effectually prevented.

While the gas produced in the tank 10 may be used for many purposes, I use it in accordance with the present invention for starting an internal combustion engine, as of an automobile, by direct pneumatic pressure. To this end, gas from the tank 10 is supplied through a pipe 35, which is preferably a branch pipe from the pipe 28 so that it may be controlled in common with the latter pipe by the hand shut off valve 29, and an automatic cut off valve to supply pipe 36 leading to the engine through the hand control valve and the distributor, of which more hereafter. The automatic cut off valve comprises casing sections 20' and 21', diaphragms 19' and 22', lock nuts 25', a head 26', and a spring 27' identical in structure with the parts 20, 21, 19, 22, 25, 26, and 27 already described. The valve stem 24' of the automatic cut off valve differs 65 from the valve stem 24 of the pressure gov-

ernor in that it has a flaring conical end 37 instead of a needle point, said flaring end 37 coöperating with a valve seat on a casing section 23' substantially identical with the casing section 23 save that the valve seat is 70 on the side of the casing remote from the diaphragms. The pipes 35 and 36 are connected to the casing section 23' in substantially the same manner as are the pipes 13 and 15 to the casing section 23 of the pressure governor. The automatic cut off valve operates, in a manner exactly the reverse of that of the pressure governor, to close the connection between the gas tank 10 and the pipe 36 when the pressure in such tank falls below a predetermined value, this predetermined value being lower than that at which the pressure governor opens. This prevents the operator from wasting the gas by continuing to draw it from the tank 10 when the pressure therein is too low to be efficient for starting the engine, and allows the generator time, only a few seconds ordinarily being necessary, to build up the pressure to an efficient value; then the automatic cut-off valve opens and allows gas to be drawn from the tank to continue the starting operation.

The pipe 36 leads to the casing 40 of the control valve. This casing has a central passage 41 provided at its two ends with outwardly and oppositely facing valve seats, with which valve heads 42 and 43, which are mounted on a common valve stem 44 smaller than the passage 41 and are spaced farther apart than are the valve seats, respectively coöperate. The valve head 42 and its valve seat are conical, while the valve head 43 and its seat may be flat, the valve head 43 preferably being faced with rubber 45 or other yieldable material on its side toward the valve seat. The valve stem 44 of the control valve is suitably connected, as by a bell crank lever 46, to be moved by a rod 47 and push knob 48, the latter conveniently being mounted on the dash board of an automobile if the apparatus is used in connection with an automobile. The control valve is biased, both by a spring 49 and by the pressure from the pipe 36 on the valve head 42, to hold said valve head against its seat and thus close the valve. When the knob 48 is pushed, the valve is opened by the separation of the valve head 42 from its seat, the valve head 43 at the same time being moved against its valve seat to prevent leakage around the valve stem. The opening of the control valve opens the pipe 36 to a pipe 50, leading from the passage 41 between the two valve 110 seats. The pipe 50 leads to an opening 51 on one side of the casing 52 of the distributor, the other side of said casing being provided with a series of openings 53 equidistant from the center of the casing and equally spaced 115 120 125 130

apart, the number of said openings 53 being equal to the number of cylinders of the engine with which the device is associated; a four cylinder engine being illustrated. The 5 openings 53 are connected by pipes 54 to valves 55 opening into the respective engine cylinders 1, 2, 3, and 4; said valves 55 being normally closed and being openable by the rod 47 when the latter is moved to open the 10 control valve. The valves 55 are substantially the same in structure as the control valve, but here the gas pressure is admitted through the opening at the side of the valve casing and discharged through the opening 15 at the end thereof, whereas on the control valve the gas is admitted through the opening at the end of the valve casing and discharged through the opening at the side thereof. Thus in each valve 55, all pressure 20 from the gas tank 10 being cut off when the control valve is closed, any pressure from the associated engine cylinder acts at all times against the head of the valve, thereby aiding the spring in keeping the valve seated 25 and preventing leakage when the starter is not being operated to start the motor. If desired, a shut off valve 29', separate from the valve 29, may be placed in the pipe 36, conveniently being located on the dashboard 30 if the device is used on an automobile. The casing 52 of the distributor is also provided with an opening 56 on the same side of the casing as but nearer the center thereof than are the openings 53, said opening 56 communicating, as by a pipe 57, with the atmosphere. 35

Mounted within the casing 52 is a rotary disk 60, which is driven at a speed proportional to that of the engine shaft 59, conveniently at one-half engine speed if the engine is of the four-cycle type. The disk 60 is thinner than the space within the casing 52, and when pressure is admitted through the pipe 50 and opening 51 is held firmly 40 against that side of the casing which is provided with the openings 53 and 56. When such pressure is relieved, the disk moves slightly away from the inner surface of the casing, and its center on the side of the disk 45 toward the opening 51 bears against a bearing ball 61, thus reducing friction to a minimum. The disk 60 is provided with a notch 62 in its periphery, such notch being of such angular length that it successively opens the various openings 53 to the space on the other side of such disk and thus to the pipe 50 during the time that the corresponding engine cylinders are on their explosion strokes, but closes the openings 53 before the 50 exhausts of such respective cylinders are opened. The disk 60 is provided on its side toward the openings 53 and 56 with a circular recess 63 which is provided with a sectorial wing 64. The circular recess continually covers the opening 56 during the rotation of the disk 60, and the wing 64 of such recess covers the various openings 53 successively. The wing 64 of this recess is so located that it opens the various engine cylinders to the atmosphere, through the openings 53 and 56, when such cylinders are on their compression strokes. This eliminates, or greatly reduces, the compressing action within the cylinders, and thus greatly diminishes the work required in starting the engine. While permissible, it is not necessary that the wing 64 of the recess open the engine cylinders to the atmosphere during the whole of their compression strokes, as ample relief is found to be obtained by connecting such cylinders to the atmosphere during the latter parts of such strokes. 70

To start the engine, the ignition circuit, if desired, first being closed as is usually done preparatory to cranking the engine, the knob 48 is pushed to open the control valve and the valves 55. This admits pressure from the tank 10, provided such pressure is sufficiently high to allow the automatic cut off valve to be open, through the opening 51 of the distributor, the notch 62, and the proper opening 53 and pipe 54, into the engine cylinder which is on its explosion stroke. At the same time, the pressure within the engine cylinder which is on its compression stroke is relieved through the recess 63 and its wing 64, coöperating with the opening 56 and pipe 57. The pressure thus supplied from the tank 10 to the cylinder on its explosion stroke operates the piston 100 within said cylinder to move the engine forward, the disk 60 being rotated with the engine at proper relative speed. As the disk 60 is rotated, gas from the tank 10 is admitted under pressure to the engine cylinders in proper succession on their explosion strokes, the compression in each of said cylinders being previously relieved to diminish the work required. After a few revolutions of the engine shaft, the knob 105 48 may be released to permit the spring 46 to close the valves 55 and the control valve. The ignition circuit must now be closed if it has not previously been closed. The engine is now in its normal condition and 110 operates under its own power, the momentum given it by the starter, carrying it past the point where the first explosion of compressed carbureted air takes place, just as in the case of cranking by hand. While the 115 starter gas, even when acetylene, is not itself an explosive mixture, and even if admitted to the firing chamber of the cylinder or cylinders of the engines at the time the ignition sparking takes place therein would not produce an explosion in the firing chamber or in the exhaust pipe or muffler, by my device the starter gas is not admitted to any cylinder while ignition sparking takes place therein; that is, it is not admitted by 120 125 130

the distributor into any cylinder until after the piston on its firing stroke has passed its ignition point and is on its downward stroke; and it is largely exhausted or withdrawn from the cylinder by the succeeding exhaust stroke of the engine and before the next compression stroke and consequently before the next succeeding ignition spark takes place in such cylinder, the operation 10 being the same in each separate cylinder of the engine. As pressure is drawn from the tank 10, water or other reagent is automatically supplied from the tank 12 to maintain the pressure in the former tank, the 15 pressure governor acting to maintain such pressure substantially constant within comparatively narrow limits, and to replenish such pressure to a value which is substantially constant within even narrower limits. 20 If, for any reason, as because the engine persistently fails to begin operating under its own power and repeated efforts to start it are required, too much gas is drawn from the tank 10, and the gas pressure is thus reduced below an efficient value for starting the engine, the automatic cut off valve is closed to give such pressure time to build up. As soon as the pressure is built up, which as heretofore shown is ordinarily 25 practically an instantaneous operation, the automatic cut off valve opens to allow the starting operation to continue.

Although my system comprises a number 30 of moving parts, these parts are all so arranged that no packings are required at any moving joints. As a result, the difficulties caused by such packings are entirely 35 eliminated.

I claim as my invention:

- 40 1. In combination, an internal combustion engine, a gas generator which produces gas under pressure sufficient to start the engine and in which the production of gas is controlled by the pressure of such produced gas, and a control valve for admitting gas from said generator to said engine.
- 45 2. In combination, an internal combustion engine, a chemical gas generator which produces gas under pressure sufficient to start the engine and in which the production of gas is controlled by the pressure of such produced gas, said generator comprising two connected compartments respectively containing a liquid and another substance 50 which react to produce the gas, and a control valve for admitting gas from said generator to said engine.
- 55 3. In combination, an internal combustion engine, a gas generator which produces gas under pressure sufficient to start the engine and in which the production of gas is controlled by the pressure of such produced gas, a control valve for admitting gas from said generator to said engine, and an automatic cut off valve for closing the connection 60 between the generator and the engine when the gas pressure in the generator falls below a predetermined value.
- 65 4. In combination, a multicylinder internal combustion engine, a gas generator which produces gas under pressure sufficient to start the engine and in which the production of gas is controlled by the pressure of such produced gas, a control valve for admitting gas from said generator to said engine, a distributor operated from the engine and directing the gas thus admitted to the engine cylinders on their explosion strokes, a valve associated with each engine cylinder and controlling its connections to the distributor, and a common operating means for all said last named valves and said control valve, said distributor being provided with ports for connecting the engine cylinders to atmosphere when they are on their compression strokes and the associated valves are open.
- 70 5. In combination, a multicylinder internal combustion engine, a gas generator which produces gas under pressure sufficient to start the engine and in which the production of gas is controlled by the pressure of such produced gas, a control valve for admitting gas from said generator to said engine, and a distributor operated from the engine and directing the gas thus admitted to the engine cylinders on their explosion strokes.
- 75 6. In combination, a multicylinder internal combustion engine, a gas generator which produces gas under pressure sufficient to start the engine and in which the production of gas is controlled by the pressure of such produced gas, a control valve for admitting gas from said generator to said engine, and a distributor operated from the engine and directing the gas thus admitted to the engine cylinders on their explosion strokes.
- 80 7. In combination, a multicylinder internal combustion engine, a chemical gas generator which produces gas under pressure sufficient to start the engine and in which the production of gas is controlled by the pressure of such produced gas, said generator comprising two connected compartments respectively containing a liquid and another substance which react to produce the gas, a control valve for admitting gas from said generator to said engine, and a distributor operated from the engine and directing the gas thus admitted to the engine cylinders on their explosion strokes.
- 85 8. In combination, a multicylinder internal combustion engine, a gas generator which produces gas under pressure sufficient to start the engine and in which the produc-

tion between the generator and the engine when the gas pressure in the generator falls below a predetermined value.

70 4. In combination, a multicylinder internal combustion engine, a gas generator which produces gas under pressure sufficient to start the engine and in which the production of gas is controlled by the pressure of such produced gas, a control valve for admitting gas from said generator to said engine, a distributor operated from the engine and directing the gas thus admitted to the engine cylinders on their explosion strokes, a valve associated with each engine cylinder and controlling its connections to the distributor, and a common operating means for all said last named valves and said control valve, said distributor being provided with ports for connecting the engine cylinders to atmosphere when they are on their compression strokes and the associated valves are open.

75 5. In combination, a multicylinder internal combustion engine, a gas generator which produces gas under pressure sufficient to start the engine and in which the production of gas is controlled by the pressure of such produced gas, a control valve for admitting gas from said generator to said engine, and a distributor operated from the engine and directing the gas thus admitted to the engine cylinders on their explosion strokes.

80 6. In combination, a multicylinder internal combustion engine, a gas generator which produces gas under pressure sufficient to start the engine and in which the production of gas is controlled by the pressure of such produced gas, a control valve for admitting gas from said generator to said engine, and a distributor operated from the engine and directing the gas thus admitted to the engine cylinders on their explosion strokes.

85 7. In combination, a multicylinder internal combustion engine, a chemical gas generator which produces gas under pressure sufficient to start the engine and in which the production of gas is controlled by the pressure of such produced gas, said generator comprising two connected compartments respectively containing a liquid and another substance which react to produce the gas, a control valve for admitting gas from said generator to said engine, and a distributor operated from the engine and directing the gas thus admitted to the engine cylinders on their explosion strokes.

90 8. In combination, a multicylinder internal combustion engine, a gas generator which produces gas under pressure sufficient to start the engine and in which the produc-

- tion of gas is controlled by the pressure of such produced gas, a control valve for admitting gas from said generator to said engine, a distributer operated from the engine and directing the gas thus admitted to the engine cylinders on their explosion strokes, and a valve associated with each engine cylinder and controlling its connections to the distributer.

5 9. In combination, a multicylinder internal combustion engine, a gas generator which produces gas under pressure sufficient to start the engine and in which the production of gas is controlled by the pressure of such produced gas, a control valve for admitting gas from said generator to said engine, a distributer operated from the engine and directing the gas thus admitted to the engine cylinders on their explosion strokes, a valve associated with each engine cylinder and controlling its connections to the distributer, and a common operating means for all said last named valves and said control valves.

10 10. In combination, a multicylinder internal combustion engine, a gas generator which produces gas under pressure sufficient to start the engine and in which the production of gas is controlled by the pressure of such produced gas, a control valve for admitting gas from said generator to said engine, a distributer operated from the engine and directing the gas thus admitted to the engine cylinders on their explosion strokes, and a valve associated with each engine cylinder and controlling its connection to the distributer, said distributer being provided with ports for connecting the engine cylinder to atmosphere when they are on their compression strokes and the associated valves are open.

15 11. In combination, a multicylinder internal combustion engine, a gas generator which produces gas under pressure sufficient to start the engine and in which the production of gas is controlled by the pressure of such produced gas, a control valve for admitting gas from said generator to said engine, a distributer operated from the engine and directing the gas thus admitted to the engine cylinders on their explosion strokes, a valve associated with each engine cylinder and controlling its connection to the distributer, said distributer being provided with ports for connecting the engine cylinder to atmosphere when they are on their compression strokes and the associated valves are open.

20 12. In combination, a multicylinder internal combustion engine, a gas generator which produces gas under pressure sufficient to start the engine and in which the production of gas is controlled by the pressure of such produced gas, a control valve for admitting gas from said generator to said engine, a distributer operated from the engine and directing the gas thus admitted to the engine cylinders on their explosion strokes, a valve associated with each engine cylinder and controlling its connection to the distributer, and a common operating means for all said last named valves and said control valves.

25 13. In combination, a multicylinder internal combustion engine, a chemical gas generator which produces gas under pressure sufficient to start the engine and in which the production of gas is controlled by the pressure of such produced gas, said generator comprising two connected compartments respectively containing a liquid and another substance which reacts to produce the gas, a control valve for admitting gas from said generator to said engine, a distributer operated from the engine and directing the gas thus admitted to the engine cylinders on their explosion strokes, and a valve associated with each engine cylinder and controlling its connection to the distributer.

30 14. A distributer for starting apparatus for internal combustion engines, comprising a casing, and a disk rotatable in said casing, said casing being provided on one side of the disk with an opening to a source of fluid supply and on the other side of the disk with a circular series of openings to the various engine cylinders and with an exhaust opening out of such circular series, and said disk being cut away to connect the openings of said series successively to said first named opening and recessed on the side toward such exhaust opening to connect the latter successively to the openings of said series as the disk is rotated.

35 15. A distributer for starting apparatus for internal combustion engine, comprising a casing having a circular series of openings for connection to the several engine cylinders and two openings outside of said series, one of said last named openings being for exhaust and the other for connection to a source of fluid supply, and a rotary member within said casing, said rotary member being provided with cut away portions for connecting each of said last named openings successively to the several openings of said series as the rotary member rotates.

40 16. In combination, a multicylinder internal combustion engine, a source of fluid pressure, a control valve for admitting fluid under pressure from said source to said engine, a distributer operated from the engine

and directing the fluid thus admitted to the engine cylinders on their explosion strokes, a valve associated with each engine cylinder and controlling its connection to the distributor, and a common operating means for all said last named valves and said control valves, said distributor being provided with ports for connecting the engine cylinders to atmosphere when they are on their compression strokes and the associated valves are open.

17. In combination, a multicylinder internal combustion engine, a source of fluid pressure, a control valve for admitting fluid under pressure from said source to said engine, a distributor operated from the engine and directing the fluid thus admitted to the engine cylinders on their explosion strokes, and a valve associated with each engine cylinder and controlling its connection to the distributor, said distributor being provided with ports for connecting the engine cylinders to atmosphere when they are on their compression strokes and the associated valves are open.

18. The method of starting a multicylinder internal combustion engine, which consists in generating a gas under sufficient pressure to operate the engine by direct fluid pressure by bringing together substances which react to produce such gas and replenishing the pressure as the gas is used by bringing together more of such substances, supplying the gas under pressure to the engine cylinders successively when on explosion stroke, and relieving the compression within the engine cylinders successively when on compression stroke.

19. The method of starting an internal combustion engine, which consists in generating a gas under sufficient pressure to operate the engine by direct fluid pressure by bringing together substances which react to produce such gas and replenishing the pressure as the gas is used by bringing together more of such substances, supplying the gas under pressure to the engine cylinder when on explosion stroke, and relieving the compression within the engine cylinders when on compression stroke.

20. The method of starting a multicylinder internal combustion engine, which consists in generating a gas under sufficient pressure to operate the engine by direct fluid pressure and replenishing the pressure as the gas is used, supplying the gas under pressure to the engine cylinders successively when on explosion stroke, and relieving the compression within the engine cylinders successively when on compression stroke.

21. The method of starting a multicylinder internal combustion engine, which consists in generating a gas under sufficient pressure to operate the engine by direct fluid pressure by bringing together substances

which react to produce such gas and replenishing the pressure as the gas is used by bringing together more of such substances, and supplying the gas under pressure to the engine cylinders successively 70 when on explosion stroke.

22. The method of starting an internal combustion engine, which consists in generating a gas under sufficient pressure to operate the engine by direct fluid pressure and replenishing the pressure as the gas is used, supplying the gas under pressure to the engine cylinder when on explosion stroke, and relieving the compression within the engine cylinder when on compression stroke. 75

23. The method of starting an internal combustion engine, which consists in generating a gas under sufficient pressure to operate the engine by direct fluid pressure by bringing together substances which react to produce such gas and replenishing the pressure as the gas is used by bringing together more of such substances, and supplying the gas under pressure to the engine cylinder when on explosion stroke. 80

24. The method of starting a multicylinder internal combustion engine, which consists in generating a gas under sufficient pressure to operate the engine by direct fluid pressure and replenishing the pressure as 95 the gas is used, and supplying the gas under pressure to the engine cylinder successively when on explosion stroke.

25. The method of starting an internal combustion engine, which consists in generating a gas under sufficient pressure to operate the engine by direct fluid pressure and replenishing the pressure as the gas is used, and supplying the gas under pressure to the engine cylinder when on explosion 105 stroke.

26. In combination, a multicylinder internal combustion engine, a gas generator which produces gas under pressure sufficient to start the engine and in which the pressure 110 is replenished by additional generation when the pressure of the gas is reduced below a predetermined value by the using of the gas, a control valve for admitting gas from said generator to said engine, a distributor operated from said engine and directing the gas thus admitted to the various engine cylinders when on explosion stroke, and a valve associated with each engine cylinder and controlling its connection to the distributor, said distributor being provided with ports for connecting the various engine cylinders to atmosphere when on compression stroke. 120

27. In combination, an internal combustion engine, a gas generator which produces gas under pressure sufficient to start the engine and in which the pressure is replenished by additional generation when the pressure of the gas is reduced below a pre- 125

determined value by the using of the gas, a control valve for admitting gas from said generator to said engine, a distributor operated from said engine and directing the gas

5 thus admitted to the engine cylinder when on explosion stroke, a valve associated with the engine cylinder and controlling its connection to the distributor, said distributor being provided with ports for connecting 70
10 the engine cylinder to atmosphere when on compression stroke.

28. In combination, an internal combustion engine, a gas generator which produces gas under pressure sufficient to start the engine and in which the pressure is replenished by additional generation when the pressure of the gas is reduced below a predetermined value by the using of the gas, and a control valve for admitting gas from 80
20 said generator to said engine.

29. In combination, a multicylinder internal combustion engine, a gas generator which produces gas under pressure sufficient to start the engine and in which the pressure is replenished by additional generation when the pressure of the gas is reduced below a predetermined value by the using of the gas, a control valve for admitting gas from 85
25 said generator to said engine, and a distributor operated from said engine and directing the gas thus admitted to the various engine cylinders when on explosion stroke, said distributor being provided with ports for connecting the various engine cylinders to atmosphere when on compression stroke.

30. In combination, an internal combustion engine, a gas generator which produces gas under pressure sufficient to start the engine and in which the pressure is replenished by additional generation when the pressure of the gas is reduced below a predetermined value by the using of the gas, a control valve 90
40 for admitting gas from said generator to said engine, and a distributor operated from said engine and directing the gas thus admitted to the engine cylinder when on explosion stroke, said distributor being provided with ports for connecting the engine cylinder to atmosphere when on compression stroke.

31. In combination, an internal combustion engine, a chemical gas generator for generating gas under sufficient pressure to operate the engine by direct fluid pressure, means for supplying gas under pressure from said generator to start said engine, said generator being capable of replenishing the gas pressure as gas is used and having 95
50 sufficient storage capacity to supply enough gas to the engine normally to start the latter.

32. In combination, an internal combustion engine, a chemical gas generator for generating gas under sufficient pressure to

operate the engine by direct fluid pressure, means for supplying gas under pressure from said generator to start said engine, said generator being capable of replenishing the gas pressure as gas is used and having 70
75 sufficient storage capacity to supply enough gas to the engine normally to start the latter, and means for automatically disconnecting the engine from the generator if the gas pressure in the latter falls below a predetermined value.

33. In combination, an internal combustion engine, a reservoir for gas under pressure, means for supplying gas from said reservoir to start said engine, means acting 80
independently of said engine for automatically replenishing the gas pressure in said reservoir when it falls below a predetermined value, and an automatic cut-off valve for closing the connection whereby the gas 85
is supplied from the reservoir in case the pressure in the reservoir falls below a lower predetermined value.

34. In combination, an internal combustion engine, a reservoir for gas under pressure, a controlling valve for supplying gas from said reservoir to start said engine by direct fluid pressure, an automatic valve responsive to the pressure in said reservoir for admitting material thereinto to replenish 90
95 the gas pressure therein, and an automatic cut-off valve for closing the connection whereby the gas is supplied from the reservoir in case the pressure in the reservoir falls below a predetermined value. 100

35. The method of starting an internal combustion engine, which consists in chemically producing a gas under sufficient pressure to move the engine, injecting such gas into the engine, and controlling the production of the gas by the pressure thereof to maintain a substantially constant pressure always available. 105

36. In combination, an internal combustion engine, a gas producer for producing a 110
gas under sufficient pressure to move the engine and for replenishing such pressure to a substantially constant value as the gas is used from the producer, and means for supplying the gas from said producer to said 115
engine to start the latter.

37. In combination, an internal combustion engine, a chemical gas producer for producing a gas and replenishing it to a substantially constant pressure as it is used, 120
said pressure being sufficient to start the engine, and means for supplying the gas from said producer to said engine.

38. In combination, an internal combustion engine, a chemical gas producer for producing a gas and replenishing it as it is used to a substantially constant pressure sufficient to start the engine, and a distributor for controlling the supply of gas from said producer to said engine. 125
130

39. In combination, a multi-cylinder internal combustion engine, a chemical gas producer for producing a combustible gas and replenishing it as it is used to a substantially constant pressure sufficient to start said engine, and a distributer receiving gas from said producer and supplying it to different cylinders of said engine.

40. In combination, a multi-cylinder internal combustion engine, a chemical gas producer for producing a gas and replenishing it as it is used to a substantially constant

pressure sufficient to start said engine, and a distributer receiving gas from said producer and supplying it to different cylinders 15 of said engine.

In witness whereof, I have hereunto set my hand and seal at Indianapolis, Indiana, this 25th day of May, A. D. one thousand nine hundred and twelve.

HARRY W. HAMILTON. [L. S.]

Witnesses:

G. B. SCHLEY,
FRANK A. FAHLE.
